COMBINED TOILET AND TANK UNIT

James L. Rutzick, St. Paul, Minn., assignor to Aquazyme
Industries, Inc., St. Paul, Minn.

Filed June 19, 1970, Ser. No. 23,570

Term of patent 14 years

Int. Cl. D23—02

U.S. Cl. D23—48

FIG. 1

FIG. 2

FIG. 3

FIG. 4

FIG. 1 is a top plan view of a combined toilet and tank unit showing my new design;

FIG. 2 is a front elevation thereof;

FIG. 3 is a rear elevation thereof; and

FIG. 4 is a bottom plan view thereof.

I claim:

The ornamental design for a combined toilet and tank unit, substantially as shown.
